S. COATES.

Gas Retort.

No. 19,686.

Patented Mar. 23, 1858.

UNITED STATES PATENT OFFICE.

S. COATES, OF NEW YORK, N. Y.

METHOD OF CLEANSING GAS-GENERATORS.

Specification of Letters Patent No. 19,686, dated March 23, 1858.

To all whom it may concern:

Be it known that I, SAUNDERS COATES, of New York, county of New York, and State of New York, have invented certain new and 5 useful Improvements in Portable Gasworks; and I do hereby declare that the following is a full, clear, and exact description of the same, reference being made to the annexed drawing, making a part of this specification, 10 which is a central vertical section of a retort of ordinary construction having my improvement attached.

My invention is an improvement in that method of cleaning the retorts employed for 15 generating olefiant gas, wherein the said cleaning is effected by burning out the carbonaceous and other residuum left from the decomposition of the fatty matters, which method of cleaning is necessarily resorted to 20 in those small retorts used in what are commonly known as "Portable-gas-works." In these a cleaning is frequently required and as, from the limited capacity of the works, the said cleaning should be performed with 25 as little interruption as possible of the process of gas making, it is effected while the retort is fully heated, by merely shutting off the flow of oil, stopping the passage for the gas into the washing-box, and admitting 30 atmospheric air into the retort, causing the interior contents to take fire, and thereby burning out not only the gas in the retort which had not yet passed over, but also the carbonaceous matters resulting from the 35 fatty matters used. A few minutes suffices to do this. The residuum is thus removed excepting only some ashes, and the generating process may then be resumed by turning on the feed again and opening the delivery 40 pipe.

My improvement consists simply in admitting the said atmospheric air into the retort at its upper part when necessary to clear it, (and this is either by lifting the 45 cover at one side, or by an air cock inserted into the said cover,) and at the same time creating a draft in the retort by means of an opening, also from the upper part, into the chimney or into the fire under the retort, 50 whereby the gaseous products of combustion will be drawn off and the air caused to enter.

I do not claim herein the general principle

of admitting air into a retort, at any place, in combination with such vent as I have described, for I am aware that the air has 55 been so admitted at or near the bottom or lower side of the retort. This method however has been found uncertain in practice, as well as dangerous to the operators, by reason of the frequent explosions which have 60 occurred in its use, since, in that, the entering air often forms an explosive mixture with the gas, whereas, by causing the air to enter, as I do, at the top, the gas burns at the surface, in a manner well known, as fast 65 as the air comes into contact with it.

At A in the annexed drawing is shown a retort of the ordinary caldron shape, having a cover (b) fitting into a groove in the usual manner, and provided with a pipe (c) communicating with the gasometer, and with a siphon (d) for admitting oil, the whole being set in a furnace, as common to this kind of works. In the cover I insert an air cock (e) and from the side of the retort, 75 near its upper part, I carry out a pipe (f). This pipe must be extended into some place where a draft is produced, as for instance, the chimney of the furnace, or, it may be, as represented, carried into the furnace 80 itself, and this arrangement I prefer, as thereby a stronger draft is produced through the pipe. The pipes (f) and (e) are provided with stop-cocks, as shown, and the 85 operation will be as follows.

When the retort needs cleaning, open the cocks in the pipes (e) and (f); the air entering at (e) causes the contents of the retort to take fire, and burn down from the surface, and the product of this combustion is drawn off through the pipe (f) into the furnace. The same effect will be produced, if preferred, by raising slightly the cover of the retort on one side, the air entering in that way causing also combustion at the surface. It will thus be seen that as the entrance of the air and the means of escape for the products of combustion are at the upper part of the retort no disturbance of the contents of the retort takes place, and hence no 90 mixture of the air with the gases can occur to form an explosive mixture, which has so often happened in those retorts in which the air is admitted at or near the bottom.

I claim

The mode of clearing the retort by the admission of atmospheric air at the top of said retort, in combination with the draft-
5 pipe for carrying off the products of combustion, the whole being arranged in the manner substantially as set forth herein.

In witness whereof I have hereunto set my hand.

S. COATES.

In presence of—

J. P. PENSSON,
S. H. MAYNARD.
